UNITED STATES PATENT OFFICE.

AVIS F. RAE, OF CHICAGO, ILLINOIS.

HOUSEKEEPER'S REMINDER.

1,026,768.

Specification of Letters Patent.

Patented May 21, 1912.

Application filed September 28, 1910. Serial No. 584,174.

To all whom it may concern:

Be it known that I, AVIS F. RAE, a citizen of the United States, residing at Chicago, in the county of Cook and State of 5 Illinois, have invented a certain new and useful Improvement in Housekeepers' Reminders, of which the following is a specification.

My invention relates to improvements in 10 memorandum devices and has for one object to provide a so-called housekeeper's reminder.

It is illustrated in one form in the accompanying drawing, wherein—

15 Figure 1 is a front elevation; Fig. 2, a section on the line 2—2 of Fig. 1; Fig. 3, a section on the line 3—3 of Fig. 1.

Like parts are indicated by like letters throughout the several figures.

20 The flat plate A which is preferably finished in white or some other light color, carries near either edge the parallel vertically disposed rods A² in bearings made up of the alternate inwardly extending loop A³

25 and outwardly extending loop A⁴. The arrows B which are rotatably mounted upon the rod A² between the loop A⁴ are finished on one side in the same color as the body of the plate and on the other side in some

30 strongly contrasting color such as black or red and are so arranged that when they point inwardly the contrasting color appears and when they point outwardly the light color appears. The surface of the

35 plate between the two groups of arrows is divided into two sections and each section is divided into a series of compartments corresponding to the arrows and in each of these sections is printed or written the name 40 of any article in common use such as salt, sugar, coffee, etc.

When the housekeeper wishes to be reminded that, for instance, she needs a supply of any article, she will rotate the arrow 45 about the rod until it points inwardly toward the desired article and when this is obtained or the matter attended to, she will rotate the arrow back until it points outwardly and the light colored side is exposed.

50 The device may be suspended in any suitable manner or in any suitable place by means of the hole C in the top of the plate

and will provide, by means of contrasting color of the arrows when they are in an operative position, an index or reminder which 55 cannot be easily overlooked.

It will be evident that while I have shown in my drawings an operative device, still many changes might be made in the size, shape and arrangement of parts without departing materially from the spirit of my invention, and I wish, therefore, that my drawings be regarded as in a sense diagrammatic.

I claim:

1. A housekeeper's reminder comprising a plate, an index thereon, a series of alternately oppositely bent loops struck from the material of the plate and adjacent one to the other, a straight rod mounted in said 70 loops, a series of pointers bent around at their inner ends and thus pivotally mounted on such rod, each between a pair of loops and in opposition one to each item in the index.

2. A housekeeper's reminder comprising a plate, an index thereon, a series of alternately oppositely bent loops struck from the material of the plate and adjacent one to the other, a straight rod mounted in said 80 loops, a series of pointers bent around at their inner ends and thus pivotally mounted on such rod, each between a pair of loops and in opposition one to each item in the index, the two sides of the different pointers 85 differing in appearance.

3. A housekeeper's reminder comprising a plate, an index thereon, a series of alternately oppositely bent loops struck from the material of the plate and adjacent one to 90 the other, a straight rod mounted in said loops, a series of pointers bent around at their inner ends and thus pivotally mounted on such rod, each between a pair of loops and in opposition one to each item in the 95 index, the two sides of the different pointers differing in appearance, that side which is exposed when the pointer is turned toward the index differing in appearance from the body of the plate.

AVIS F. RAE.
